US0D1111205S

(12) **United States Design Patent** (10) **Patent No.:** **US D1,111,205 S**
(45) **Date of Patent:** **** Feb. 3, 2026**

(54) **PRESENTER**

(71) Applicant: **Xiaohong Yang**, Zhangjiajie (CN)

(72) Inventor: **Xiaohong Yang**, Zhangjiajie (CN)

(**) Term: **15 Years**

(21) Appl. No.: **29/922,698**

(22) Filed: **Dec. 25, 2023**

(51) **LOC (15) Cl.** **26-02**

(52) **U.S. Cl.**

USPC **D26/37**

(58) **Field of Classification Search**

(57) **CLAIM**

The ornamental design for a presenter, as shown and described.

DESCRIPTION

FIG. 1 is a front, top and right side perspective view of a presenter, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the presenter that form no part of the claimed design.

1 Claim, 8 Drawing Sheets
